DRY CLEANING AND LAUNDRY COLLECTION DEPOSITORY

Jack N. Shuman, 126 W. Tremont Ave., Charlotte, N.C.

Filed Sept. 18, 1963, Ser. No. 76,626

Term of patent 14 years

(Cl. D58—17)

Fig. 2

Fig. 1

FIG. 1 is a perspective view of a dry cleaning and laundry collection depository embodying my new design;

FIG. 2 is a perspective view taken from the opposite side of FIG. 1 with the doors in open position;

FIG. 3 is a vertical cross sectional view thereof taken through the center, and

FIG. 4 is a view similar to FIG. 3, showing the doors in one position.

The characteristic feature of my design resides in the particular configuration of the drop bin on the uppermost portion in open position in combination with the shelf as particularly shown in FIG. 2. The rear of the depository of the illustrated embodiment is substantially plain.

I claim:

The ornamental design for a dry cleaning and laundry collection depository, as shown and described.
